UNITED STATES PATENT OFFICE.

WILLIAM MAIDENS, OF COLUMBUS, OHIO.

GAME APPARATUS.

1,076,503.

Specification of Letters Patent.

Patented Oct. 21, 1913.

Application filed December 17, 1912. Serial No. 737,270.

To all whom it may concern:

Be it known that I, WILLIAM MAIDENS, a citizen of the United States, residing at Columbus, in the county of Franklin and 5 State of Ohio, have invented new and useful Improvements in Game Apparatus, of which the following is a specification.

This invention is an improved game apparatus, embodying a helical spiral track, 10 means to turn the same and a ball or balls to run on and be elevated by the spiral track and deposited in a cage at the upper end thereof and intended to exercise the skill of the operator, the invention consisting in 15 the construction, combination and arrangement of devices hereinafter described and claimed.

In the accompanying drawing:—Figure 1 is a perspective view of a game apparatus 20 constructed in accordance with my invention. Fig. 2 is a vertical sectional view of the same.

In accordance with my invention, I provide a circular base 1 which has a vertical 25 peripheral wall 2. On the base is arranged a helical spiral track 3 which comprises a bottom 4 and vertical side walls 5. The lower end of this spiral track bears directly on the base and against the wall 2 and the 30 upper end of the spiral track terminates in a table 6 on which is a cage 7. The cage has an opening 8 to establish communication between the upper end of the track and the interior of the cage and the cage is here 35 shown as circular in form, open at its upper end and provided with a washer 9 which forms a cover therefor. A shaft 10 passes vertically through the centers of the base, the table and the cage and washer and has a 40 threaded upper portion and is secured to the base by nuts 11 and to the table washer and cage by a nut 12 which bears under the table and a nut 13 which bears on the upper side of the washer.

45 In connection with the apparatus herein-

before described, I employ three balls 14. By placing the balls first in the base and then turning the device by means of its shaft 10, the balls may, if the device is skilfully operated, be caused to run up the 50 spiral helical track and to pass through the opening 8 into the cage.

I would have it understood that my improved game apparatus is preferably made of paste-board but may be made of any 55 other suitable material.

While I have herein shown and described a preferred form of my invention, I would have it understood that changes may be made in the form, proportion and construction of the several parts without departing from the spirit of my invention and within the scope of the appended claim.

I claim:—

The herein described game apparatus 65 comprising a shaft having a threaded portion, a base secured on the shaft, and having a surrounding upwardly extending flange or wall, a spiral helical track rising from the base and terminating at its upper end in a table, the said table having an opening through which the threaded portion of the shaft extends, a cage arranged on said table and having an opening in one side to communicate with the upper end of 70 the track, the said cage being concentrically arranged with the shaft, a cover on the cage and through which the shaft extends and nuts on the threaded portion of the shaft 75 and bearing one on the cover of the cage 80 and the other under the table and clamping the cage, the cover and the table together and, hence, supporting the upper end of the spiral helical track.

In testimony whereof I affix my signature in presence of two witnesses.

WILLIAM MAIDENS.
